CLAIM

The ornamental design for a watchstrap display, as shown and described.

DESCRIPTION

FIG. 1 is a front and side perspective view of a watchstrap display showing my new design with one of the doors in an open position;

FIG. 2 is a plan view of the back;

FIG. 3 is a plan view showing the side not visible in FIG. 1;

FIG. 4 is a top view;

FIG. 5 is a bottom view; and,

FIG. 6 is a front and side perspective view of a second embodiment of that shown in FIG. 1, the rear and opposite side being a mirror image thereof.
